CLAIM

The ornamental design for a housing for energy storage power supply as shown and described.

DESCRIPTION

1. Housing for energy storage power supply

1.1 : Perspective

1.2 : Perspective

1.3 : Front

1.4 : Back

1.5 : Left

1.6 : Right

1.7 : Top

1.8 : Bottom

The parts represented by dashed lines do not form part of the claimed design; FIG. 1.1 to FIG. 1.8 show a housing for energy storage power supply of the present design; The housing for energy storage power supply is used to protect the internal components of the energy storage power supply.
